(57) **CLAIM**

The ornamental design for a Yahrzeit memorial candle holder, as shown and described.

DESCRIPTION

FIG. 1 is a front, right side perspective view of the Yahrzeit memorial candle holder, showing a base with a candle holding cavity, a back with two holes for rings, and two rings located in the two holes;

FIG. 2 is a right side perspective view of the Yahrzeit memorial candle holder, showing a lit candle in the candle holding cavity in the base of the Yahrzeit memorial candle holder and three memorial cards on the two rings located in the two holes in the back of the Yahrzeit memorial candle holder, the left side being a mirror image thereof;

FIG. 3 is a top view of the Yahrzeit memorial candle holder; FIG. 4 is a front view of the Yahrzeit memorial candle holder, also showing the lit candle and an exemplary memorial card on the two rings and situated in front of the back of the yahrzeit memorial candle holder;

FIG. 5 is a back view of the Yahrzeit memorial candle holder;

FIG. 6 is a front view of a second embodiment of the Yahrzeit memorial candle holder shown in the preceding figures, the only difference being in the configuration of the back, it being understood that all other surfaces are the same as those of the first embodiment; and,

FIG. 7 is a top view of a third embodiment of the Yahrzeit memorial candle holder shown in the preceding figures, the only difference being in the configuration of the base, it being understood that all other surfaces are the same as those of the first embodiment.

The bottom (not shown) of the Yahrzeit memorial candle holder is flat and unornamented. The candle and memorial cards, shown in broken lines, are provided for illustrative purposes only and from no part of the claimed design.
